UNITED STATES PATENT OFFICE.

JIRO MIYABARA, OF TOKIO, JAPAN.

FEED-WATER HEATER FOR WATER-TUBE BOILERS.

SPECIFICATION forming part of Letters Patent No. 633,699, dated September 26, 1899.

Application filed July 27, 1899. Serial No. 725,241. (No model.)

To all whom it may concern:

Be it known that I, JIRO MIYABARA, a subject of the Emperor of Japan, and a resident of Tokio, in the Empire of Japan, have invented 5 a new and useful Improvement in Feed-Water Heaters for Water-Tube Boilers, of which the following is a specification.

This invention has for its object to provide a simple, convenient, and efficient water-tube 10 boiler in which there shall be an effective circulation of water and steam, and has more particularly for its object to provide a structure in which the water which is fed to the boiler may be circulated back and forth between the 15 top drums or steam-chambers of the boiler, so as to become heated to a material degree by the escaping gases before it is permitted to escape into the said drums.

My present invention is more particularly 20 directed to an improvement in the structure set forth in my British Patent No. 9,131, dated April 30, 1896, for improvement in water-tube boilers; and it consists in providing a feed-water inlet-pipe which enters one of the compartments in a hollow casing in one of the top 25 drums or steam-chambers, a plurality of series of feed-water tubes leading back and forth between the compartments in the said hollow casing and compartments in a similar 30 hollow casing in the other top drum or steam-chamber, and a feed-water outlet-pipe leading from one of the compartments in the last-named hollow casing to the interior of the steam-chamber within which the said hollow 35 casing is located.

A practical embodiment of my invention is represented in the accompanying drawings, in which—

Figure 1 is a sectional side elevation of my 40 improved boiler. Fig. 2 is a front elevation, partially in section, of the same; and Fig. 3 is a sectional plan view showing the arrangement of the feed-water tubes and their adjacent parts.

The water-tube boiler to which I have applied my improved structure comprises two 45 water-walls arranged to form the front and back of a combustion-chamber, each composed of horizontal cylindrical vessels arranged one above another and connected together by interposed junction-boxes or short vertical tubes, the upper drums of the two

series being denoted by A A', which drums serve as steam-chambers. The two walls thus constructed are connected by sets of diagonal 55 or inclined heating-tubes that extend across the combustion-chamber above the fire-grate, there being provided within the water vessels, except the top and bottom ones, diaphragms or deflectors, which are so arranged as to direct 60 the streams of water and steam arriving from the upper ends of one of the lower groups of tubes into the lower ends of the next upper group of tubes, thereby permitting the remaining portions of the water-tubes to act as 65 down-takes.

Flanged hollow casings B B' are secured along the interiors of the hollow drums A A', which casings may be made of cast or wrought steel or other suitable metal and so constructed 70 that they may be taken off in order to clean, examine, or replace the feed-water-heating tubes. The said hollow casings are divided into a plurality of compartments by transverse partitions b b'. 75

A plurality of groups of feed-water-heating tubes C cross between the two uppermost cylindrical drums or steam-chambers, which tubes open into the several compartments in the hollow casings B B', so as to form a circulation back and forth, as indicated by the 80 arrows in Fig. 3 of the drawings.

Sets of tubes D are located at each extreme side of the boiler, which tubes cross between the front and back steam-chambers A A' and 85 serve to convey the steam from the back steam-chamber A' to the front chamber A.

A feed-water inlet-pipe E leads from some suitable source of supply (not shown) into the interior of the end compartment of the 90 hollow casing B at one side of the boiler, and a feed-water outlet-pipe F leads from the end compartment of the hollow casing B' at the other side of the boiler, which outlet-pipe extends downwardly to a point near the bottom 95 of the steam-chamber A' and thence along the same for a considerable distance. This portion of the outlet-pipe F, which extends along near the bottom of the hollow drum or steam-casing A', is preferably perforated, so as to 100 distribute the water along the said chamber.

By the structure hereinabove set forth the water being fed to the boiler is caused to circulate back and forth across the combustion-

chamber, so that the water is heated before it is permitted to be discharged into the back steam drum or casing.

It is evident that slight changes might be resorted to in the form and arrangement of the several parts without departing from the spirit and scope of my invention. Hence I do not wish to limit myself strictly to the structure herein set forth; but

10 What I claim is—

1. In a water-tube boiler the combination with the front and back top drums or steam-chambers thereof, of hollow casings located within the said top drums, feed-water-heating tubes crossing between the two drums and communicating with the hollow casings, a feed-water inlet-pipe arranged to enter one of the said hollow casings and a feed-water outlet-pipe arranged to lead from the other hollow casing, the said feed-water outlet-pipe having open communication with the interior of the drum within which it is located, substantially as set forth.

2. In a water-tube boiler, the combination with the front and rear top drums thereof, of feed-water-heating tubes crossing between the two drums, hollow casings located within the said top drums, the said casings being provided with partitions so as to form junction-pockets for the said feed-water tubes, a

feed-water inlet-pipe leading to the end compartment in one of the hollow casings and a feed-water outlet-pipe leading from the end compartment of the other hollow casing, the said water-outlet pipe having open communication with the hollow drum within which it is located substantially as set forth.

3. In a water-tube boiler the combination with the two top drums thereof and tubes connecting the drums at the extreme sides of the boiler, of feed-water-heating tubes crossing between the two drums intermediate the first-mentioned side tubes, hollow casings located within the top drums for receiving the ends of the feed-water-heating tubes, a feed- water inlet-pipe leading to one of the hollow casings and a feed-water outlet-pipe leading from the other of the hollow casings and in open communication with the interior of the drum within which it is located, substantially as set forth.

In testimony that I claim the foregoing as my invention I have signed my name, in presence of two witnesses, this 6th day of July, 1899.

JIRO MIYABARA.

Witnesses:

JOHN MCLEAN,
K. GOYODE.
